A. A. Hickey
ATTORNEY

UNITED STATES PATENT OFFICE.

JOHN A. DICKERMAN, OF BRIDGEPORT, CONNECTICUT, ASSIGNOR TO REMINGTON ARMS COMPANY, INC., A CORPORATION OF DELAWARE.

PRIMER.

Application filed September 1, 1920, Serial No. 407,306. Renewed February 8, 1928.

This invention relates to primers of the type used for igniting the explosive charge of cartridges and has for its object to provide a primer comprising an anvil constructed so that it will not readily drop out of the cup. Another object is to so construct the anvil that the blast produced by the explosion of the detonating substance is directed into the flash hole of the cartridge shell, thereby assuring improved ignition of the explosive charge.

A further object is to reduce puncturing of the primer cups by so constructing the anvil that it may be made of relatively soft material.

Other objects and advantages will appear in the following description of a preferred form of the invention taken in connection with the attached drawing, wherein:—

20 Fig. 1 is an enlarged axial cross sectional view of a cartridge shell and primer made according to the present invention.

Fig. 2 is an enlarged axial cross sectional view taken at right angles to the view of 25 Fig. 1, and

Fig. 3 is a plan view, further enlarged, of the anvil of said primer.

In said views, the numeral 4 represents a cartridge shell of usual construction, formed 30 with a primer pocket 5 and a flash hole 6. The primer which is located in said pocket preferably comprises a cup containing the detonating material 9 and having cylindrical side walls 7 and a bottom 8.

35 The anvil comprises the circular top plate 13, having its entire periphery bearing within said cup. The plate may be formed with the downwardly extending flange 12 preferably bent at right angles to increase 40 its area of contact with the cup. It is slit at 14 and 15 and the intervening metal strip is bent inward, forming an anvil bridge 16 of substantially the form shown in Fig. 1 the sides of which are open to provide a flash 45 passage to permit the flash to reach the propelling powder charge. The apex 17, of the anvil bridge lies against or adjacent the detonating substance and serves as a support against which the detonating substance is 50 driven by the impact of the firing pin or striker.

An anvil of this construction has the advantage of being very firmly held in the cup on account of the large area of its bearing

surface and because it has a bearing around 55 its entire circumference.

Where the anvil has a bearing only part way around, it distorts the cup and it is held in place merely by the force required to distort the cup. In the primer of the present 60 invention, the cup is slightly expanded by the anvil and it contracts upon the anvil with an equal force at all points of its periphery thereby absolutely preventing the accidental removal of the anvil.

65 The metal of the top plate 13 outside of the slits 14 and 15 is preferably left in place forming baffle plates 18 and 19 which serve to direct the blast of the detonation toward the axis of the primer and cartridge so that 70

they will the more easily pass through the relatively small flash hole 6 to ignite the explosive charge. In constructing primers it is very essential that the size of the flash 75 passage be very accurately determined for the reason that if the passage is too small the primer may be blown out on account of the pressure of the gases generated by the detonating material; if it is too large the primer may be blown out by the pressure of 80 the gases of the propelling charge. The baffle plates 18 and 19 serve as a barrier to the direct flow of the gases, and provide a tortuous flash passage which is of sufficient 85 area and the proper shape to allow the flash to reach the propelling powder while setting up sufficient "wire drawing" effect to prevent the gases of the propelling charge blowing out the primer.

Such an anvil possesses great rigidity 90 against contraction and it may therefore be made of soft metal, as copper. Anvils as usually constructed must be made of fairly hard material, as brass in order to provide sufficient strength and rigidity. As the cups usually consist largely of copper they are 95 so soft that they will be easily punctured by the blow of the firing pin or striker when supported by an anvil of hard metal. When a soft metal, as an alloy of more than about 85% copper is used for anvils the tendency to puncture is very greatly reduced. On account of the great rigidity against contraction possessed by the anvil of the present invention it may be made of copper or 100 other soft material, whereby the percentage of punctured primers is reduced to a minimum.

Having now thus described the invention, and a specific embodiment thereof, as well as the function and mode of operation of the same, what I claim as new and desire to secure by Letters Patent of the United States is:—

6. 1. In a primer, the combination of a cup and an anvil therein comprising a circular plate having its entire periphery bearing in said cup, a part of said plate extending inward to form an apex against which the detonating material may bear and another part of the plate forming a baffle.
10. 2. In a primer, the combination of a cup and an anvil therein comprising a circular plate having its entire periphery bearing in said cup, a part of said plate comprising a strip near the center thereof having been bent inward to form an apex against which 45
15. 3. An anvil for primers comprising a plate formed with spaced slits and having the material between the slits bent out to form an anvil apex and a flash passage.
20. 4. An anvil for primers comprising a plate formed with spaced slits and having the material between the slits bent out to form an anvil apex and a flash passage, and having its edges bent at right angles to form 50
25. 5. In a primer, the combination of a cup and anvil, said anvil comprising a circular plate formed with flanges bearing within said cup, said plate being formed with slits 55
30. 6. In a primer, the combination of a cup and an anvil therein comprising a circular plate having its entire periphery bearing in said cup, a part of said plate extending inward to form an apex against which the detonating material may bear, and to form a flash passage.
35. 7. In a primer, the combination of a cup and an anvil therein comprising a circular plate having its entire periphery bearing in said cup, a part of said plate comprising a strip near the center thereof having been bent inward to form an apex against which 60
40. 8. In a primer, the combination of a cup and an anvil comprising a plate, said plate comprising an inwardly bent apex and flash passage forming portion, a flat portion forming a baffle adjacent said flash passage.
45. 9. An anvil for primers comprising a plate formed with spaced slits having the material between the slits bent out to form 65
50. an anvil apex and a flash passage, its edges bent at right angles to form flanges and baffle portions between said flanges and said passage.

and the material between said slits bent inward to form an anvil apex and a flash passage.

6. In a primer, the combination of a cup and an anvil therein comprising a circular plate having its entire periphery bearing in 40

said cup, a part of said plate extending inward to form an apex against which the detonating material may bear, and to form a flash passage.

7. In a primer, the combination of a cup 45

and an anvil therein comprising a circular plate having its entire periphery bearing in

said cup, a part of said plate comprising 50

a strip near the center thereof having been

bent inward to form an apex against which 55

the detonating material may bear, and to form a flash passage.

8. In a primer, the combination of a cup

and an anvil comprising a plate, said plate

comprising an inwardly bent apex and flash

passage forming portion, a flat portion

forming a baffle adjacent said flash passage.

9. An anvil for primers comprising a

plate formed with spaced slits having the

material between the slits bent out to form 60

an anvil apex and a flash passage, its edges

bent at right angles to form flanges and

baffle portions between said flanges and said

passage.

In witness whereof I have signed my

name hereto this 30th day of August 1920.

JOHN A. DICKERMAN.
